UNITED STATES PATENT OFFICE.

LUTHER C. BALDWIN, OF PROVIDENCE, RHODE ISLAND, ASSIGNOR TO U. S. BOBBIN & SHUTTLE COMPANY, OF PROVIDENCE, RHODE ISLAND, A CORPORATION OF NEW JERSEY.

SHUTTLE.

1,212,881.

Specification of Letters Patent. Patented Jan. 16, 1917.

Application filed March 6, 1916. Serial No. 82,273.

To all whom it may concern:

Be it known that I, LUTHER C. BALDWIN, a citizen of the United States, residing at Providence, in the county of Providence and State of Rhode Island, have invented 5 a new and useful Improvement in Shuttles, of which the following is a specification.

This invention relates to certain new and 10 useful improvements in shuttles and pertains more particularly to a bobbin gripping device for the shuttle.

The primary object of the invention is 15 to provide a bobbin gripping device the use of which permits practically the full strength of the wood of the shuttle to be retained, as distinguished from gripping devices which in being incorporated in the shuttle necessitate cutting away of the wood 20 of the shuttle to an extent which weakens the shuttle.

Further, the invention aims to provide a 25 gripping device which may be drop forged so as to thereby possess increased strength and retention of elasticity in excess of gripping devices otherwise formed or made.

Still further, the invention aims to provide a gripping device which possesses minimum of parts, easily manufactured 30 and assembled, to enable the device to be secured with the use of but one screw or bolt, and to necessitate the boring of but two holes in the shuttle for securing of the device.

35 In the drawings, Figure 1 is a fragmentary top plan view of a shuttle with the present invention applied thereto. Fig. 2 is a section on the line 2—2 of Fig. 1. Fig. 3 is a section on the line 3—3 of Fig. 2. 40 Fig. 4 is a top plan detail view of the guide member, and Fig. 5 is a detail perspective view of one of the jaws.

The guide consists of a stem 1 of cylindrical form, or of the shape of a round 45 rod, to which is attached at the front end of the stem, a metal plate shaped to form an inclined nose or guide proper 2, and a base member 3 the sides of which project beyond the respective sides of the stem. 50 The jaws are similar in form and each comprises a shank 4 of substantially concavo-convex cross-section to receive the stem therebetween as depicted in Fig. 3, the shanks being bent or curved at 5 and having 55 the jaw proper terminals 6.

The shuttle is provided with a bored hole 7 in which is received the shanks 4 and stem 1, and is further provided with a bored hole 8 which intersects hole 7. The stem 1 is also provided with a transverse hole 9 so that a bolt 10 may be passed through the holes 8 and 9, and through holes 11 in the jaws and secured by nut 12. The hole 7 extends longitudinally of the shuttle and for a length sufficient to receive the shanks 4, the latter being of a length so as to be firmly held by the walls that the hole 7 forms. The bottom of the shuttle is cut away at 13, to receive the base 3 of the guide 2, and the guide 2 has an out-turned 60 upper end 14 which rests against the wall 15 of the shuttle, so as to thus provide a means for supporting the guide at its upper end, and to also assist in holding the entire gripping device against movement. 65

In operation the shanks 4 are placed on opposite sides of the stem 1 with their holes 11 in register with the hole 9 of the stem, the lower edges of the jaws being supported on the extended sides of base 3 of the guide, 70 whereupon the parts are slid into hole 7 and the bolt 10 placed through the hole 8 and holes 9, 11, 11, and the nut 12 applied, whereby the entire structure is secured in a rigid and effective manner. It will be 75 seen that since the jaws are separate and independent of one another, same may be drop forged with the result that they are possessed of increased strength and retain their elasticity to an extent in excess of 80 that possessed by jaws otherwise formed. Since the jaws rest on the base 3 they are supported by the latter, and the base 3 in turn is prevented from moving downwardly by contacting with the wall formed by cut- 85 out 13 of the shuttle. 90

The two holes 7 and 8 are the only holes which the shuttle possesses, consequently full strength of the shuttle is retained.

Having thus described my invention, what 100 I claim as new and desire to secure by Letters Patent is—

1. In combination with a shuttle having a longitudinal hole and a cross hole intersecting the first hole, a stem, a guide secured to the front end of the stem and having an inclined part, the top end of which is turned outwardly to engage the shuttle and having a base which underlies the stem and extends on opposite sides thereof, a pair of separate 105 110

jaws having concavo-convex shanks engaged on opposite sides of the stem and in said longitudinal hole and seating on the side portions of the base of the guide, said jaw shanks and stem having registering openings which align with the cross hole, and a bolt passed through said registering openings and cross hole.

2. In combination with a shuttle having a longitudinal opening, a stem having a guide, a pair of jaws having concavo-convex shanks engaged on opposite sides of the stem, and means to secure the parts in the shuttle opening extending through the shanks, stem, and shuttle.

3. In combination with a shuttle having a longitudinal round opening, a stem, and a pair of jaws having shanks which conformably fit over said stem, said jaws when engaged with said stem having a substantially circular cross-section so as to be capable of being driven in the opening.

4. In combination with a shuttle having a longitudinal opening, a stem, and a pair of jaws having shanks which latter fit over said stem and have free side edges which

confront each other, the stem and shanks being received in said opening.

5. In combination with a shuttle having a longitudinal opening, a stem, and a pair of jaws having shanks which latter fit over said stem so as to substantially inclose the entire periphery thereof and being received in said opening.

6. In combination with a shuttle having a bored opening, a stem, and jaws engaged over the stem and formed so as to be capable of being driven into the opening with the stem.

7. In combination with a shuttle having a bored opening, a stem, and jaws engaged with the stem and with the latter received in the opening so as to be held by the walls defining the opening.

In testimony whereof I have signed my name to this specification in the presence of two subscribing witnesses.

LUTHER C. BALDWIN.
